(57) **CLAIM**

We claim the ornamental design for sampling device, as shown and described.

DESCRIPTION

FIG. 1 is a front elevation view of the device.

FIG. 2 is a rear elevation view thereof.

FIG. 3 is a side elevation view thereof. The view from the opposite side being a mirror image thereto.

FIG. 4 is an upward perspective view thereof. The view from the adjacent front corner is a mirror image thereto.

FIG. 5 is a downward perspective view thereof. The view from the adjacent front corner is a mirror image thereto.

FIG. 6 is an upward perspective view thereof. The view from the adjacent rear corner is a mirror image thereto; and,

FIG. 7 is a downward perspective view thereof. The view from the adjacent rear corner is a mirror image thereto.
